SAFETY DEVICE FOR LOOMS

Henri Bricout, Paris, France, assignor to Comptoir Linier, Paris, France, a society of France

Application October 25, 1945, Serial No. 624,374
In France June 13, 1945

5 Claims. (Cl. 139—353)

1

The present invention relates to devices for stopping a loom when a thread is broken, has got loose or has come to its end. The invention is more especially, although not exclusively, concerned, among these devices, with those used in connection with electrically operated round looms.

The chief object of the invention is to provide a device of this type which is better adapted to meet the requirements of practice than those used for the same purpose up to the present time.

Other objects of my invention will result from the following detailed description of a specific embodiment thereof with reference to the accompanying drawing, given merely by way of example, and in which the only figure is a diagrammatical view of a stopping device of the kind above mentioned.

In the following description, it will be supposed that the stopping device is applied to an electrically operated round loom of the kind described in my co-pending application for "Electric round looms," Ser. No. 624,424, filed of even date with the present application.

In such a loom, one or several shuttles 1 are driven with a continuous movement of rotation about a vertical axis A—A, through the action of electro-magnets 2, preferably disposed under said shuttles, respectively, and which are fed with current from a direct current source 3 through fixed brushes 4¹ and 4² cooperating with rings 5¹ and 5² carried by the rotating portion of the loom. This portion of the loom is driven by an electric motor 6 fed with alternating (three-phase) current from a distinct source.

The shuttle or shuttles move between two sheets 8¹ and 8² of warp threads so as automatically to cooperate therewith, the weft thread 9 being fed from each shuttle and the reversing movement of sheets 8¹ and 8² with respect to each other being obtained by means of automatically operated heddles 10¹ and 10². The fabric 11 is pulled upwardly as it is being made, through means not shown by the drawing, being guided between two annular parts 12¹ and 12².

Heddles 10¹ and 10² are uniformly distributed, in two rows, around the axis of the loom, which is fed with a multiplicity of warp threads 13 running upwardly so as to form a cylindrical sheet around said loom. These warp threads 13 are fed from rollers or warp beams provided at the bottom part of the loom (and not visible on the drawing) toward said heddles through the intermediate of elastic guides constituted by flexible rods 14 mounted on a fixed support 14¹, each of

2

these rods 14 forming at its end an open loop 14² through which passes the corresponding warp thread. Preferably, a group of several pairs of heddles is mounted on a common support plate 5 (at right angles to the plane of the drawing) so that all the heddles 10¹ of this group move together, same as the heddles 10² of the group in question.

When a thread 13 ceases to be stretched, due 10 to the fact that it is broken, or has got loose or has come to its end, rod 14 is no longer inclined toward the right by the tension of said thread and, as a result of its spring mounting at 14³, said rod is inclined in the opposite direction so 15 as to be brought into contact with a metallic bar 15. Each of these bars 15 extends opposite the length of a group of heddles and is therefore common to all the rods 14 that serve to the guiding of the threads 13 controlled by this group of 20 heddles. Metallic bar 15 is connected through a wire 16 with one of the terminals of an electric luminous signal 17, for instance a red lamp and with one of the terminals of an electric acoustic signal 18, for instance an electric bell 25 giving a shrill sound. The other terminals of these signals are connected in parallel, through a wire 19, with the positive terminal of direct current source 3. The negative terminal of this source is connected, through wire 20, to three 30 relays 21 in series which, when energized, simultaneously open switches 22 respectively provided in the feed wires 23 connecting main switch 24 with the loom driving motor 6. The output of this series of relays is connected, through a wire 25, with the common support 14¹ of flexible rods 14, said wire 25 being advantageously permanently earthed, i. e. connected to the metallic frame 36 of the loom, as shown by wire 36¹. Wire 19 is also connected, through a wire 26, with the brush 4¹ of the electro-magnets, while the other brush 4² is connected, through a wire 27, to the negative terminal of direct current source 3. A hand 40 operated switch 28 is inserted in wire 19, and a suitable measurement apparatus 29 (ammeter) 45 is inserted in wire 27.

On the feed wires 23 of motor 6 is branched 50 an alternating current relay 30 which, when not energized, causes a braking device to act on a rotary part of the loom, for instance a belt brake 31 cooperating either directly with a shaft 32 operatively connected with the rotating portion of the loom. When current ceases to be fed to motor 6, this brake is applied by a spring 33, of adjustable strength.

The metallic shuttle 1 carries, on its outer lat-

eral wall, a brush 34 which bears constantly, during the angular movement of said shuttle between the two sheets of warp threads, against a circular vertical comb 35 in the slots of which are respectively engaged the warp threads corresponding to the group of heddles that is considered. This circular comb 35 rests upon the metallic frame 36 of the loom through an annular piece 37 made of an insulating material. This comb 35 is connected through a wire 38 (in which is inserted a normally closed switch 39) to one of the terminals of an electric luminous signal, for instance a blue lamp 40 and to one of the terminals of an electric acoustic signal, for instance an electric bell 41 giving a deep sound (that is to say signals wholly different from those corresponding to the warp threads), the other terminal of these signals 40 and 41 being connected to the wire 19 which leads, as above stated, to the positive terminal of the direct current source 3.

Shuttle 1 carries, on the inner lateral face thereof, and through the intermediate of an insulating part 42, an arm 43 provided with a brush 44 permanently applied against a metallic ring 45 connected, at 46, with the metallic frame 36 of the loom and constituting, for instance, one of the roller tracks of the shuttle. Arm 43 carries a flexible rod 47 provided, at the end thereof, with an open loop for guiding the thread 9 fed by the shuttle. When thread 9 is stretched, rod 47 is kept out of contact with the metallic body of the shuttle. If thread 9 breaks, or gets loose or if the spool of the shuttle is at its end, rod 47 is released, and automatically straightens itself, coming into contact with the metallic body of the shuttle or with a finger 48 carried by said body. Thus, I obtain the closing of the circuit 38 of signals 40 and 41 together with that of the circuit 25 of relays 21, which causes these signals to be operated and motor 6 to be stopped, while brake 31 is applied.

It is known that before the loom is started or after a shuttle or several shuttles have been replaced, the weft, or wefts, 9 fed therefrom are loose, so that flexible rods 47 are applied against the metallic bodies of the corresponding shuttles. Therefore, the loom cannot be started since its motor cannot be fed with current (switches 22 being kept open by relays 21). In order to obviate this difficulty, according to the invention, switch 39 is temporarily opened, which places signals 40, 41 and relays 21 out of circuit. Motor 6 is then fed with current and as soon as the loom has worked sufficiently for tensioning weft or wefts 9 (which moves rods 47 away from the corresponding shuttles), switch 39 is closed so that the stopping device can work normally.

With this stopping device, distinct and different signals are brought into play according as the breakdown concerns warp threads or weft threads. In the case of a warp thread, the corresponding flexible rod 14 is released and comes into contact with the corresponding bar 15 which brings into action the signals corresponding to this bar and immediately stops the loom by stopping the feed of current to motor 6 and applying brake 31. The person that is supervising the loom can, by observing the nature of the acoustic signal (shrill sound) and of the visual signal (blue light) know where there is some repair to be done. As soon as the rod 14 that had been released is kept at a distance from bar 15 by the tensioning of the thread (which has been repaired or replaced), the loom can be started

again by the closing of switches 22 and the release of the brake. The same effects are obtained when the breakdown concerns one of the weft threads, this breakdown being signalled by the appearance of a red light and the emission of a deep sound acoustic signal. In this case, it may be necessary, in order to start the loom after the stopping thereof, to open auxiliary switch 39 for a certain time.

10 Main switch 24, auxiliary switches 28 and 39, relays 21 together with switches 22, measurement apparatus 29, visual signals 17 and 40, and acoustic signals 18 and 41 may be mounted on a common board placed within easy reach of the person that is operating the loom.

The stopping device according to the present invention is applicable to all kinds of looms.

While I have, in the above description, disclosed what I deem to be a practical and efficient embodiment of the present invention, it should be well understood that I do not wish to be limited thereto as there might be changes made in the arrangement, disposition and form of the parts without departing from the principle of the present invention as comprehended within the scope of the appended claims.

What I claim is:

1. For use in connection with an electric loom including a motor for driving it, a safety device 30 which comprises, in combination, means for braking at least one part of the loom drive, electro-magnetic means for keeping, when fed with current, said braking means out of action, means for feeding current both to said braking means 35 and said motor, means responsive to variations of tension of both the warp and the weft threads for cutting off said current feed means in case of lack of tension of any of said threads, at least two different alarm means, means responsive to 40 variations of tension of the warp threads for operating one of said alarm means in case of lack of tension of one of said warp threads, and means responsive to variations of tension of at least one weft thread for operating the other alarm means 45 in case of lack of tension of said weft thread.

2. For use in connection with an electric loom including a motor for driving it, a safety device which comprises, in combination, means for feeding current to said motor, means for cutting off 50 said current feed means, at least two different alarm means, a plurality of electric circuits, one for at least each warp thread, each of said circuits including one of said alarm means and said current feed cut-off means, means in each of 55 said circuits responsive to variations of tension of the corresponding warp threads for keeping said circuit open as long as said warp thread is stretched and closing said circuit in case of lack of tension of said warp thread, at least one electric circuit including the other of said alarm means and said current feed cut-off means, and means in said last mentioned circuit responsive to variations of tension of a weft thread for keeping said last mentioned circuit open as long 60 as said weft thread is stretched and closing said circuit in case of lack of tension of said weft thread.

3. For use in connection with an electric loom including a motor for driving it, a safety device 70 which comprises, in combination, means for braking at least one part of the loom drive, electro-magnetic means for keeping, when fed with current, said braking means out of action, means for feeding current both to said motor and said 75 braking means, means for cutting off said cur-

rent feed means, at least two different alarm means, a plurality of electric circuits, one for at least each warp thread, each of said circuits including one of said alarm means and said current feed cut-off means, means in each of said circuits responsive to variations of tension of the corresponding warp threads for keeping said circuit open as long as said warp thread is stretched and closing said circuit in case of lack of tension of said warp thread, at least one electric circuit including the other of said alarm means and said current feed cut-off means, and means in said last mentioned circuit responsive to variations of tension of a weft thread for keeping said last mentioned circuit open as long as said left thread is stretched and closing said circuit in case of lack of tension of said weft thread.

4. For use in connection with an electric loom including a motor for driving it, a safety device which comprises, in combination, means for feeding current to said motor, means for cutting off said current feed means, at least two different alarm means, a plurality of electric circuits, one for at least each warp thread, each of said circuits including one of said alarm means and said current feed cut-off means, means in each of said circuits responsive to variations of tension of the corresponding warp threads for keeping said circuit open as long as said warp thread is stretched and closing said circuit in case of lack of tension of said warp thread, at least one electric circuit including the other of said alarm means and said current feed cut-off means, means in said last mentioned circuit responsive to variations of tension of a weft thread for keeping said last mentioned circuit open as long as said weft thread is stretched and closing said circuit in case of lack of tension of said weft thread, and switch means in said last mentioned circuits for permitting the restarting of said loom after a repair necessitated by a lack of tension of said weft thread.

5. For use in connection with an electric loom including a motor for driving it, a safety device which comprises, in combination, means for braking at least one part of the loom drive, electro-magnetic means for keeping, when fed with current, said braking means out of action, means for feeding current both to said motor and said braking means, means for cutting off said current feed means, at least two different alarm means, a plurality of electric circuits, one for at least each warp thread, each of said circuits including one of said alarm means and said current feed cut-off means, means in each of said circuits responsive to variations of tension of the corresponding warp threads for keeping said circuit open as long as said warp thread is stretched and closing said circuit in case of lack of tension of said warp thread, at least one electric circuit including the other of said alarm means and said current feed cut-off means, means in said last mentioned circuit responsive to variations of tension of a weft thread for keeping said last mentioned circuit open as long as said weft thread is stretched and closing said circuit in case of lack of tension of said weft thread, and switch means in said last mentioned circuits for permitting the restarting of said loom after a repair necessitated by a lack of tension of said weft thread.
